UNITED STATES PATENT OFFICE

132,341

DESIGN FOR A LAPEL PIN

Paul P. Smilo, New York, N. Y.

Application April 9, 1942, Serial No. 106,511

Term of patent 3½ years

To all whom it may concern:

Be it known that I, Paul P. Smilo, a citizen of the United States of America, residing in New York city, county of New York, and State of New York, have invented a new, original, and ornamental Design for a Lapel Pin, of which the following is a specification, reference being had to the accompanying drawing, forming part thereof, wherein,

I claim:

The ornamental design for a lapel pin, substantially as shown,

PAUL P. SMILO,
